[57] CLAIM

The ornamental design for a light and motion sensor, as shown.

DESCRIPTION

FIG. 1 is a perspective view of a light and motion sensor according to the present invention in an exemplary configuration;

FIG. 2 is a front elevation view of the light and motion sensor unit of FIG. 1;

FIG. 3 is a side elevation view of the light and motion sensor unit of FIG. 1;

FIG. 4 is a rear elevation view of the light and motion sensor unit of FIG. 1;

FIG. 5 is a top plan view of the light and motion sensor unit of FIG. 1; and,

FIG. 6 is a bottom plan view of a light and motion sensor of FIG. 1.

FIG. 1.

fig. 3.

fig. 5.
